UNITED STATES PATENT OFFICE.

CHARLES H. SMOOT, OF NEW YORK, N. Y., ASSIGNOR TO RATEAU, BATTU, SMOOT COMPANY, OF NEW YORK, N. Y., A CORPORATION OF NEW YORK.

CENTRIFUGAL BLOWER.

1,218,223.

Specification of Letters Patent.

Patented Mar. 6, 1917.

Application filed August 7, 1913. Serial No. 783,448.

To all whom it may concern:

Be it known that I, CHARLES H. SMOOT, a citizen of the United States of America, residing in the city, county, and State of New York, have invented certain new and useful Improvements in Centrifugal Blowers, of which the following is a true and exact description, reference being had to the accompanying drawings, which form a part thereof.

My present invention relates to centrifugal blowers, and particularly to centrifugal blowers adapted for operation at high speed, as, for instance, one directly connected to and driven by a steam turbine or a high speed electric motor.

The general object of my invention is to provide an improved blower of the type referred to.

More specifically, one object of my invention is to provide an impeller structure adapted by its strength, weight, and shape for operation at very high speeds. I accomplish this object of my invention by forming the impeller blades integral with the impeller shaft in order to get the necessary strength on the one hand and on the other hand to increase the so called "critical speed" of the blower. A second object of the invention is to provide means for delivering the air to each set of impeller blades employed in such a manner as to reduce the shock losses. This feature of my invention is of special importance in connection with the type of impeller which I prefer to employ and in which the air is delivered to the spaces between adjacent radial impeller blades comparatively close to the axis of the impeller. This object of my invention I attain by providing directing nozzles adjacent the inlet to the impeller chambers and arranged to convert the pressure of the fluid passing to the impeller chamber into velocity directed in the direction of rotation of the impeller so that the fluid is given a rotary motion about the axis of the impeller approximately equal to the rotational velocity of the impeller.

A third object of the invention is to provide an impeller and diffusion chamber construction and arrangement which will minimize the leakage through the clearance spaces between the edges of the impeller blades and the sides of the impeller chamber from the space between, and at the side

edges of one pair of impeller blades, and the corresponding spaces between adjacent pairs of impeller blades; and which will permit the impeller blades to be made of sufficient width to avoid mechanical difficulties when the impeller operates at high speeds in cases where the volume of the fluid discharged is small and the diffusion chamber surrounding the impeller chamber is correspondingly narrow. This I accomplish by making the diffusion chamber substantially narrower measured in a direction parallel to the axis of the impeller than the tips of the impeller blades and of course narrower also than the impeller chamber.

The various features of novelty which characterize my invention are pointed out with particularity in the claims annexed to and forming a part of this specification. For a better understanding of the invention, however, and of the advantages possessed by it, reference should be had to the accompanying drawings and descriptive matter in which I have illustrated a form in which my invention may be embodied.

Of the drawings:

Figure 1 is a sectional elevation taken on the line 1-1 of Fig. 2;

Fig. 2 is a transverse section taken on the line 2-2 of Fig. 1; and

Fig. 3 is a transverse section taken on the line 3-3 of Fig. 1 but on a smaller scale.

In the drawings A represents the casing of a centrifugal blower and is formed with an inlet A' for air or other gaseous fluid to be compressed which opens into the annular inlet chamber A². The chamber A² communicates adjacent its center with an impeller chamber A³ which is surrounded by a diffusion chamber A⁴. The diffusion chamber A⁴ communicates at its outer edge with the intermediate inlet chamber A⁵. The latter communicates adjacent its center with the high pressure impeller chamber A⁶. The impeller chamber A⁶ is open at its periphery to a diffusion chamber A⁷ which communicates at its periphery in turn with the usual volute collecting chamber A⁸. The impeller casing is also formed with bearing boxes A⁹ in which are journaled the reduced shaft end portions B' of the rotary impeller B. The impeller B is provided with one set of radial blades B² working in the wheel chamber A³ and with a second set

of radial blades B^3 working in the high pressure impeller chamber A^6 . In the preferred construction illustrated, the body, blades B^2 and B^3 , and shaft end portions 5 B' of the impeller, are formed in one integral structure. The formation of the impeller in a one piece structure as described is highly advantageous where high rotative speeds are desired, and when it is also desired that the machine should operate below 10 its so called "critical speed".

Those skilled in the art will understand that the integral shaft and blade construction inherently tends toward a high "critical speed" of the shaft, since the critical 15 speed of a shaft of given length is increased by increasing the stiffness of the shaft, and is decreased by increasing the weight of the shaft and the parts carried by it. The construction 20 obviously gives the maximum stiffness of shaft and strength of connection between the shaft and blades possible with a given radial depth of blade and diameter of circle touched by the tips of the blades 25 and thus permits of a high peripheral speed at the tips of the blades. Furthermore, the fact that the inner ends of the blades come closer to the axis of the shaft than would be possible if a separate hub structure were 30 employed or the blades were not integral with the shaft, makes it possible to keep the diameter of the circle touched by the tips of the blades, when the latter are of a given radial depth, smaller than would 35 otherwise be possible. This in turn makes it possible to obtain an increased angular velocity with a given peripheral velocity than would otherwise be possible. There is a distinct advantage also, in a blower of 40 the type described, in admitting the air, to be compressed, to the blades as close to the axis of the impeller wheel as is possible, and the integral shaft and blade construction described permits of the admission of the air 45 at the least possible distance from the axis of the wheel.

To reduce to a practical minimum the shock losses occurring as the air or other fluid to be compressed enters the spaces between the impeller blades, I provide adjacent and surrounding the inlet eye of each 50 impeller chamber, a series of nozzles formed of blades marked C in the case of the low pressure impeller chamber, and C' in the 55 case of the high pressure impeller chamber. These blades are arranged to convert the pressure of the fluid passing into the corresponding impeller chamber largely into velocity and to give this fluid a rotational 60 velocity in the same direction as, and approximately equal to the rotational velocity of the impeller. This permits the fluid to enter the impeller without the shock due to an abrupt change in velocity or direction of 65 velocity and thus greatly minimizes the so

called shock losses commonly occurring at the point at which the fluid passes into the impeller. This feature of my invention is especially important in the case of the impeller of the kind shown in which the blades 70 are radial and extend into close proximity of the axis of rotation of the impeller shaft. The blades C and C' may be used with or without the usual guide blades D employed to guide the fluid from the upper circumference of the inlet chamber for each impeller to the point of entering the impeller wheel and to prevent the formation of a vortex in which energy and pressure would be wasted. In practice I ordinarily prefer 80 to employ the guide blades or vanes D .

In the preferred construction illustrated the annular diffusion chambers A^4 and A^7 surrounding, and opening at their inner edges to the impeller chambers are each 8 made substantially narrower, measured in a direction parallel to the axis of the impeller, than the corresponding impeller blades at their outer ends or tips. This arrangement possesses two important advantages in the 9 case of high speed impellers. In the first place the thickness of the diffusion chamber is fixed by the conditions of operation and particularly by the volume of the fluid discharged into the diffusion chamber from the 9 impeller chamber which it surrounds. When the volume of fluid thus discharged is comparatively small and the diffusion chamber consequently narrow, the practice heretofore followed of making the axial width of 1 the tips of the blades as small as, or less than the thickness of the diffusion chamber results in blades which are not wide enough to have the desired strength and thickness to resist the mechanical strains to which 1 they are subjected. In the second place and of even more importance under some operating conditions I find that the leakage from the space between, and open at the side edges of, one pair of impeller blades into 1 the corresponding spaces between adjacent pairs of impeller blades, through the clearance space necessarily provided between the side edges of the impeller blades and the side walls of the impeller chamber is substantially reduced by the increased width of the impeller blades which is permitted when this width is not controlled by the thickness of the diffusion chamber. This decreased leakage follows from the fact that 1 the total pressure which each impeller blade exerts upon the air passing through the space between that impeller blade and an adjacent blade is fixed and constant for a particular discharge volume and for particular pressures at which the fluid passes to and is discharged from the impeller, and is independent of the width of the blade. If the impeller blades be made narrow the differential of the pressures per square inch

on the front and back faces of each blade is high, whereas if the impeller blades be wide this pressure difference is low, and the greater the area of the impeller blade the less the difference in pressure on the opposite sides of the blade. The reduction in the difference in the pressures on the opposite sides of each blade of course tends directly to a corresponding reduction in the 10 amount of leakage from the side edges of each blade and a consequent reduction in the energy losses resulting from such leakage.

It will be apparent to those skilled in the 15 art that the novel features of construction and arrangement specified are of general utility in single stage as well as in multistage blowers. They are of especial utility, however, in the case of multistage blowers 20 wherein the difficulties incident to the use of single stage blowers are multiplied.

While in accordance with the provisions 25 of the statutes I have illustrated and described the best form of my invention now known to me, it will be apparent to those skilled in the art that changes may be made in the form of the apparatus disclosed without departing from the spirit of my invention, and that under some conditions certain 30 features of my invention may be used without a corresponding use of other features.

Having now described my invention, what I claim as new and desire to secure by Letters Patent, is:

35 1. In a centrifugal blower, the combination with a rotary impeller having the spaces between adjacent blades open at the sides of the impeller, of a casing formed with an impeller chamber and a surrounding diffusion chamber opening from the periphery of the impeller chamber and of a thickness measured axially of the impeller substantially less than the width of the impeller blades at their outer ends.

40 2. In a centrifugal blower, the combination with a rotary bladed impeller, of a cas-

ing formed with an impeller chamber having a lateral inlet opening across which the inner ends of the impeller blades project, a diffusion chamber into which the impeller 50 chamber opens at its outer edge, an inlet passage opening to said impeller chamber through said inlet opening and a set of nozzles located in said inlet passage adjacent to but not contracting said inlet opening and 55 adapted to reduce the pressure and increase the velocity of the fluid passing into the impeller chamber through said inlet opening and to give said fluid a rotational velocity in the direction of the impeller rotation. 60

3. In a centrifugal blower the combination with a rotary bladed impeller having radial blades, of a casing formed with an impeller chamber, a diffusion chamber into which the impeller chamber opens at its 65 outer edge, an inlet chamber along side of the impeller chamber and a central lateral opening, across which the inner ends of the impeller blades project, connecting said inlet and impeller chambers and a set of nozzles located in said inlet chamber and surrounding said opening, and adapted to reduce the pressure and increase the velocity 70 of the fluid passing into the impeller chamber from said inlet chamber and to give said 75 fluid a rotational velocity in the direction of the impeller rotation.

4. A rotary impeller adapted for operation at very high peripheral speeds comprising a shaft or body portion and unshrouded radial blades integral therewith and projecting radially therefrom. 80

5. A rotary impeller adapted for operation at very high peripheral speeds comprising a shaft or body portion and two 85 sets of unshrouded radially extending blades integral therewith and projecting radially therefrom.
